(57) **CLAIM**

The ornamental design for an anatomically fitted belt, as shown and described.

DESCRIPTION

FIG. 1 is a perspective view thereof;

FIG. 2 is a rear elevational view thereof;

FIG. 3 is a front elevational view thereof;

FIG. 4 is a top view thereof;

FIG. 5 is a side view thereof (the view from the other side is a mirror image); and,

FIG. 6 is a bottom view thereof.

The dashed broken lines in FIGS. 1–6 do not form a part of the claimed design.
